UNITED STATES PATENT OFFICE

161,830

REFLECTING LAMP SHADE

Greta Magnusson Grossman, Beverly Hills, Calif.

Application December 24, 1949, Serial No. 6,837

Term of patent 14 years

(Cl. D48—16)

To all whom it may concern:

Be it known that I, Greta Magnusson Grossman, a subject of King George VI of England, residing in Beverly Hills, county of Los Angeles, and State of California, have invented a new, original, and ornamental Design for a Reflecting Lamp Shade, of which the following is a specification, reference being had to the accompanying drawing, forming part hereof; in which:

Fig. 1 is a top plan view of a reflecting lamp shade, showing my new design.

Fig. 2 is a side elevational view thereof.

Fig. 3 is a longitudinal sectional view, as taken on line 3—3 of Fig. 1.

Figs. 4 and 5 are cross-sectional views taken on the respective lines 3—3 and 4—4 of Fig. 2.

I claim:

The ornamental design for a reflecting lamp shade, substantially as shown.

GRETA MAGNUSSON GROSSMAN.
